CLAIM

The ornamental design for card delivering toy, as shown and described.

DESCRIPTION

FIG. 1 is a first perspective view of card delivering toy showing the claimed new design;

FIG. 2 is a second perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

In the drawings, the broken lines depict portions of the article that form no part of the claimed design.
